PRIMING MIXTURE

Joseph D. McNutt, New Haven, Conn., assignor,
by mesne assignments, to Winchester Repeating Arms Company, a corporation of Maryland

No Drawing. Application November 6, 1931,
Serial No. 573,517

8 Claims. (Cl. 52—4)

This invention relates to improvements in priming mixtures for small arms ammunition, and more particularly to a non-corrosive priming mixture of the non-mercuric type.

5 In producing the priming mixtures forming the subject matter of my invention, I employ an initiator consisting of diazodinitrophenol and a sensitizer. As a sensitizer I preferably employ tetrazene, although other materials may be substituted 10 therefor, such as metallic azides. I also preferably employ oxidizing agents which will produce a non-corrosive residue. The word tetrazene is used in this specification in the manner in which it is commonly employed in the ammunition industry 15 and designates the compound sometimes referred to as guanylnitrosaminoguanyl tetrazene, see the French patent to Rathsburg No. 671,800.

Heretofore mercury fulminate has been generally used as the initiator in priming mixtures 20 for small arms ammunition. It possesses many advantages and it has been difficult to find other materials to be used in place of mercury fulminate which would produce as satisfactory results, even though considerable effort has been 25 made to eliminate mercury fulminate from priming mixtures. While it possesses certain advantages, it also possesses certain disadvantages. Amalgamation of the cartridge cases caused by 30 the free mercury produced by the decomposition of the mercury fulminate when the cartridge is exploded prevents reloading of center fire cartridges. By employing an initiator in which no mercury fulminate is present, this amalgamation is eliminated which permits reloading and re-use 35 of center fire cartridge cases. The priming mixture of my invention also possesses advantages for use in rim fire primers. It has greater stability on storing and therefore permits the ammunition to be used and better results obtained after it has 40 been stored for long periods of time.

A suitable priming mixture for center fire cartridges may be formed by mixing the following ingredients in substantially the following proportions:

45 Diazodinitrophenol 12 to 18%, preferably 15%
Barium nitrate 25 to 40%, preferably 35%
Tetrazene 1 to 4%, preferably 3%
Antimony sulphide 8 to 18%, preferably 17%
Lead peroxide 15 to 25%, preferably 20%
50 Calcium silicide 8 to 20%, preferably 10%

Proportions of these ingredients may, of course, be varied, depending upon the commercial strength of the ingredients and to meet the requirements of various uses of the mixture.

The ingredients are first thoroughly and homogeneously mixed and then poured into individual pellets of the proper size for the individual charges in the customary way, by means of a charge plate provided with perforations adapted to mold pellets of the proper size. These pellets are then loaded into primer cups in the usual way and the primer cups then assembled in the cartridge cases.

The initiator forming the subject matter of the present invention may also be employed in rim fire priming mixtures. In producing a rim fire priming mixture I find it advisable to add not only a sensitizer, such as tetrazene to the diazo- 10 dinitrophenol, but to also employ a booster. For 15 this purpose I preferably employ basic lead azide. A suitable priming mixture for rim fire use may be formed by mixing the following ingredients in the following proportions:

Diazodinitrophenol	15 to 20%, preferably 17%	20
Basic lead azide	6 to 12%, preferably 10%	
Tetrazene	4 to 7%, preferably 6%	
Barium nitrate	20 to 30%, preferably 25%	
Lead peroxide	12 to 20%, preferably 16%	
Ground glass	20 to 28%, preferably 26%	25

As in the center fire mixtures the proportions of the ingredients may be varied depending upon the properties desired in the individual case and the commercial strength of the ingredients. The 30 rim fire mixture is prepared in the usual way, poured into individual pellets of the proper size for the individual charges by means of a charge plate in the usual manner and then transferred to empty rim fire cartridge shells. The priming 35 mixture is then forced to distribute itself into the hollow rim of the cartridge shell by spinning the shell in the customary machine. The shells are then loaded with powder and bullets in the customary way.

40 I claim:

1. A priming mixture for small arms ammunition comprising diazodinitrophenol, tetrazene, barium nitrate, lead peroxide, calcium silicide and antimony sulphide. 45
2. A priming mixture for small arms ammunition comprising from 12 to 18% of diazodinitrophenol, from 1 to 4% tetrazene, from 25 to 40% barium nitrate, from 15 to 25% lead peroxide, from 8 to 20% calcium silicide and from 8 to 18% antimony sulphide. 50
3. A priming mixture for small arms ammunition comprising substantially 15% diazodinitrophenol, substantially 35% barium nitrate, substantially 3% tetrazene, substantially 17% anti-

55

mony sulphide, substantially 20% lead peroxide and substantially 10% calcium silicide.

4. A priming mixture for small arms ammunition comprising diazodinitrophenol, basic lead azide, tetrazene, barium nitrate, lead peroxide and ground glass.

5. A priming mixture for small arms ammunition comprising from 15 to 20% diazodinitrophenol, from 6 to 12% basic lead azide, from 10 4 to 7% tetrazene, from 20 to 30% barium nitrate, from 12 to 20% lead peroxide and from 20 to 28% ground glass.

6. A priming mixture for small arms ammu-

tion comprising substantially 17% diazodinitrophenol, substantially 10% basic lead azide, substantially 6% tetrazene, substantially 25% barium nitrate, substantially 16% lead peroxide and substantially 26% ground glass.

7. A priming mixture comprising an admixture of guanylnitrosaminoguanyl tetrazene and diazodinitrophenol.

8. A priming mixture comprising an admixture of guanylnitrosaminoguanyl tetrazene, diazodinitrophenol, an oxidizing ingredient and a fuel ingredient.

JOSEPH D. McNUTT.
